United States Patent Office.

E. G. MATTHEWS, OF BOOTHBAY, MAINE.

Letters Patent No. 76,487, dated April 7, 1868.

IMPROVEMENT IN DORY-BOAT KNEES.

The Schedule referred to in these Letters Patent and making part of the same.

KNOW ALL MEN BY THESE PRESENTS:

That I, E. G. MATTHEWS, of Boothbay, in the county of Lincoln, and State of Maine, have invented certain new and useful Improvements in Dory-Boat Knees, of which the following is a full, clear, and exact description, reference being had to the accompanying drawings, forming a part of this specification, in which—

Figure 1 represents so much of a knee as is necessary to illustrate my invention.

Figure 2 represents a longitudinal central section; and

Figure 3 represents a bottom view.

To enable those skilled in the art to which my invention belongs to make and use the same, I will proceed to describe it more in detail.

In the drawings, the parts marked A A are pieces of wood cut out lengthwise of the grain of the wood, and fitted or jointed to abut against each other, as shown at *a*, fig. 2. The under sides of the pieces A A are cut out as shown at *b b*, to receive the under flanges, *c c*, of the peculiarly-shaped metal knee-supports B B, which are made with under flanges, *c c*, and upper flanges, *d d*, and curved upper guards, *e e*, the latter joining the flanges *d d* at each end, as fully shown in figs. 1 and 2. The upper guards, *e e*, not only shield the flanges *d d* from injury at the points *f*, but they also allow of a circulation of air past the joint *a*, which prevents decay and rot at the joint *a*.

The flanges *c c* are fitted in flush with faces *g g* of the pieces A A, so that the bottom boards of the boat can be nailed or spiked to the central parts, *h h*, of the pieces A A, to make a tight fit, and yet have a support against the flanges *c c*.

Knees for dory boats, as heretofore constructed, most of them being sawed out, and often cut across the grain of the wood, have been very liable to split or open, and thus render the boat unserviceable. All such objections are, however, obviated by my improved knee.

The metal knee-supports B B are firmly screwed or bolted to the pieces A A, as indicated in the drawings, and their construction is such that they give great strength to the knee, and at the same time prevent all liability of injury to the joint, both above and below, while affording proper ventilation about the upper part of the joint, as before described.

Having described my improved dory-boat knee, what I claim therein as new and of my invention, and desire to secure by Letters Patent, is—

A dory-boat knee in which the wooden parts, A A, are combined with the metal supporting-plates B B, provided with the flanges and guards *c d e*, under the arrangement and for operation as herein shown and specified.

E. G. MATTHEWS.
